UNITED STATES PATENT OFFICE.

HENRY GALLAGER, OF SAVANNAH, GEORGIA, ASSIGNOR OF THREE-FOURTHS
TO JOHN J. McDONOUGH AND M. A. O'BYRNE, OF SAME PLACE.

CAR-COUPING.

SPECIFICATION forming part of Letters Patent No. 593,464, dated November 9, 1897.

Application filed August 25, 1897. Serial No. 649,523. (No model.)

To all whom it may concern:

Be it known that I, HENRY GALLAGER, of Savannah, in the county of Chatham and State of Georgia, have invented certain new and useful Improvements in Car-Couplings, of which the following is a specification, reference being had to the accompanying drawings and to the numerals of reference marked thereon.

10 My invention relates to that class of car-couplings known as "twin-jaw," "vertical-plane," or "Janney" car-couplings, the object being to produce an improved car-coupling of this class which shall be cheap, simple 15 in construction, positive in action, and free from the liability of uncoupling while in use.

In general terms my invention embraces the ordinary form of draw-head and swinging knuckle, the latter having the usual tailpiece 20 to engage the locking mechanism, which in this instance consists of a block having an arm by which it is operated to unlock the knuckle. A curved lever having a vertical movement and also a swinging movement on 25 suitable pivots is placed behind the locking-block, which in the act of uncoupling swings under the elevated locking-block and retains it in its elevated position ready for action.

In the drawings, Figure 1 is a vertical longitudinal section through my improved car-coupling, showing the parts in position when the knuckle is closed. Fig. 2 is a similar view with the knuckle open. Fig. 3 is a horizontal section on the line 3 3. Figs. 4 to 6 are 35 detail views.

Similar numerals of reference indicate similar parts in the respective figures.

The draw-head 1 and the knuckle 2 are similar in general outline to such as are at present in use, except as hereinafter pointed out. Within the draw-head 1 is a curved lever 3, from the sides of which project pivots 4, which support the lever in vertical slots 5, formed in the side walls of the draw-head. The curved lever 3 is adapted to rock on its pivots and to be raised vertically, the pivots 4 moving in the slots 5. The curved lever 3 is of the form shown in Figs. 4 and 5, the upper portion being bifurcated. From the outer side of each bifurcation 6 extends one of the pivots 4, each pivot being a short distance below the upper end of its bifurcation. From the pivots the

lever 4 curves downward and forward in a sharp turn, the lower portion being substantially horizontal. Shoulders 7 extend laterally from the lower portion of the curved lever 3, from which also projects in a downward direction a foot-piece 8, which is adapted to pass into an opening 9, formed through the bottom of the draw-head.

10 is the locking-block, from which an arm 11 projects upward through an opening 12 in the top of the draw-head. By means of the said arm the locking-block is operated. A lip 13 extends forward from the top of the 15 block, while on the rear thereof is a stud 14. When in an uncoupled position, the locking-block 10 rests on the horizontal portion of the curved lever 3, as represented in Fig. 2.

The knuckle 2 has a tailpiece 15, curved 20 horizontally, as shown, the upper surface of which is beveled on its convex side, as indicated at 16. A projection 17 is formed on the end of the tailpiece, the use of which is hereinafter described. Before coupling the knuckle 25 is turned outwardly, which brings the tailpiece out of the draw-head, as will be seen by reference to Figs. 2 and 3. The curved lever is swung forward, so that its lower part is in a horizontal position, with the foot-piece 8 30 raised out of the opening 9 and resting on the bottom of the draw-head. The locking-block rests on the horizontal part of the lever, while its arm passes between the bifurcations 6 and through the opening 12 in the draw-head.

As the knuckle swings around in the act of coupling, the tailpiece first engages the foot-piece 8 and moves the curved lever 3 backward until the foot-piece reaches the opening 9, at which time the curved lever drops bodily, 40 the pivots 4 sliding in the slots 5. The horizontal portion of the curved lever will then be in an inclined position, as in Fig. 1, causing the locking-block to slide forward until it strikes the tailpiece, its lip 13 overlapping the 45 bevel 16 thereon, which raises the locking-block and holds it up until the end of the tailpiece has passed it. The locking-block then drops down between the tailpiece and the side of the draw-head, locking the knuckle closed 50 and forming a strong abutment for the tailpiece. The projection 17 on the tailpiece prevents the locking-block from moving forward 55 out of the draw-head, while its backward

movement is prevented by the stud 14 striking the lower end of the curved lever 3. To uncouple the parts, the locking-block is raised usually by means of a chain attached to rock- 5 arm (not shown) and to the arm 11 of the locking-block 10, which latter engages the bifurcations 6 and raises the curved lever until its foot-piece is disengaged from the opening 9, when it will swing forward partly by gravity and partly by the lifting force. This forward movement causes the curved lever to strike the tailpiece and throw open the knuckle and assume the position shown in Fig. 2 to form a support for the locking-block.

15 The curvature given to the bifurcated lever 3 is important from the fact that when in an uncoupled position its lower part forms a support for the locking-block and when in a coupled position the same part assumes an 20 inclined position of such pitch as will cause the locking-block to slide into its proper position for coupling. Should the curved lever from any cause whatever be retained in its coupled position while the knuckle is in its 25 open position, the locking-block would rest on the floor of the draw-head, as indicated in Fig. 6. In this position as the knuckle is in the act of coupling the bevel 16 of the tailpiece engages the lip 13 of the locking-block 30 and raises it, being assisted by the lower portion of the curved lever 3, which at this time is in an inclined position, thus permitting the stud 14 on the locking-block to ride thereon. The outward movement of the knuckle being 35 limited, the stud 14 on the locking-block prevents the said block from falling out of the draw-head behind the tailpiece when the coupling is open.

I claim as my invention—

40 1. In a car-coupling, in combination with a draw-head, a pivoted knuckle having a curved tailpiece, the said tailpiece having a projection on its end, a locking-block having a stud on its rear side, and a curved lever 45 pivoted behind the locking-block, the ar-

angement being such, that when the parts are locked, the locking-block will be prevented from moving forward by the projection on the tailpiece, and from moving backward by the stud abutting against the lower 50 edge of the curved lever, substantially as set forth.

2. In a car-coupling, in combination with a draw-head a knuckle pivoted thereto, a locking-block, and a lever pivoted in slots in 55 the sides of the draw-head, the said lever, which has a foot-piece on its lower end being so curved that when swung forward and supported by the foot-piece, the said lower end will be substantially horizontal and support 60 the locking-block, and when swung back, it will assume an inclined position and direct the locking-block forward into engagement with the knuckle, substantially as set forth.

3. In a car-coupling, in combination with 65 a draw-head, a pivoted knuckle provided with a curved tailpiece, the latter having a beveled surface and a projection on its end, a locking-block having a lip on its front side and a stud on its rear side, and a curved lever pivoted 70 in slots in the draw-head to allow of a vertical movement, and adapted to swing under the locking-block when the latter is raised, and to be pushed back by the tailpiece in the act of coupling, to permit the locking-block 75 to fall between the end of the said tailpiece and the draw-head, whereby the knuckle may be locked in its closed position, and the locking-block held against forward or backward movement by the projection on the tailpiece 80 and the stud on the locking-block striking the end of the curved lever, substantially as set forth.

In testimony whereof I have hereunto set my hand and affixed my seal, this 9th day of 85 August, 1897, at the said city of Savannah.

HENRY GALLAGER. [L. S.]
